UNITED STATES PATENT OFFICE.

JOHN GOETTEL, OF BOSTON, MASSACHUSETTS.

CAR-COUPING.

SPECIFICATION forming part of Letters Patent No. 590,703, dated September 28, 1897.

Application filed December 14, 1896. Serial No. 615,691. (No model.)

To all whom it may concern

Be it known that I, JOHN GOETTEL, of Boston, in the county of Suffolk and State of Massachusetts, have invented a new and useful Improvement in Car-Couplers, of which the following, taken in connection with the accompanying drawings, is a specification.

My invention relates to that class of car-couplers that are automatic in their locking action and when uncoupled are always ready to automatically lock when the cars to which they are attached come together; and it consists in an arrangement by which the operation of uncoupling releases the jaw, throws it open, and secures the locking-block and its holding-latch in such positions that the holding-jaw is free to swing back into its coupling place and to self-lock itself.

My improved coupler is illustrated in the accompanying drawings, in which—

Figure 1 is a plan of one of my couplers, the holding-jaw being represented as in its holding position. Fig. 2 is a view showing a part in horizontal section, the holding-jaw shown in full lines as closed and locked and in dotted lines as open. Fig. 3 is a view showing the coupler in front elevation, the holding-jaw being omitted, so that the other parts may be clearly seen. Fig. 4 is a view in vertical section taken on line xx of Fig. 1. Fig. 5 is a front elevation, the holding-jaw being omitted, as in Fig. 3, the locking-block being represented as in its raised position ready to drop into its locking position when the holding-jaw is closed. Fig. 6 is a detail view showing a modification of the block-holding latch.

The draw-bar A, of which my coupler device is a part, may be of any desired style and construction. The part A² of the coupler-head is fixed and is made substantially as shown in Figs. 1 and 2.

The swinging holding-jaw B B' is pivotally held by the bolt B². The rear part B' of the jaw (see Fig. 2) is adapted to swing in back of the locking-block E. (See Figs. 2 and 4.) The locking-block E is made fast to a square bolt E' by means of a pin E². (See Fig. 2.) This pin E² can be inserted or withdrawn through the opening A³ when desirable to at-

tach or remove the block E from the bolt E'. 50 For the purpose of holding the locking-block E up, so as to leave the end B' of the holding-jaw B B' free to move, thus allowing the said jaw to open, I have a latch H, pivoted at H'. This latch is so hung and balanced that its 55 tendency is to fall forward and under the locking-block E whenever the said block is raised up. (See Fig. 5.) The latch H has upon its front side a projection H², so located that when the rear part B' of the holding-jaw 60 B B' swings backward in the act of closing it comes in contact with the said projection and acting through it forces the latch to the left and out from under the locking-block, allowing it to fall in front of the part B', and thus 65 locking the holding-jaw in its closed position, as shown in Figs. 2 and 4.

The function of the bent lever D, which swings on a pivot D³, is to throw out the holding-jaw B B' when the locking-block E is 70 raised. The movement of the bent lever D is caused by the projection E³, which as the block is raised comes in contact with the upper end D² of the lever, and swinging it upward causes its lower end D' to force the end 75 B' of the holding-jaw B inward, thus causing the jaw to open.

In Fig. 6 I have shown a device to take the place of the latch H. This modification consists of a hook K, pivotally hung at K³ to the 80 shell A' of the coupler. The horizontal part K' serves to hook under the block E and hold it up in the same manner that the latch H would.

K² is a small projection against which the 85 rear part B' of the holding-jaw acts in the same manner and for the same purpose as it would on the projection H² on the latch H.

I claim—

In a car-coupler a holding-jaw pivotally attached to the draw-bar and having a rearward end adapted to engage with projections on a laterally-swinging latch and throw it out of its position, said laterally-swinging latch adapted to engage with and hold the locking-block up out of its locking position, said locking-block adapted to fall before the rear end 95 of the holding-jaw and lock it, also having a

projection adapted to come in contact with a bent lever and through it throw the holding-jaw open, the said bent lever adapted to be operated by the projection on the locking-block and to open the holding-jaw, substantially as and for the purpose set forth.

5 In testimony whereof I have signed my

name to this specification, in the presence of two subscribing witnesses, on this 2d day of December, A. D. 1896.

JOHN GOETTEL.
